(57) **CLAIM**

The ornamental design for a rail vehicle, as shown and described.

DESCRIPTION

This application contains subject matter related to the following co-pending U.S. design patent application:

Application Ser. No. 29/588,585, filed Dec. 21, 2016 and entitled "Rail Vehicle."

FIG. 1 is a front, top and left side perspective view of a rail vehicle according to the design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged view of the portion shown in BOX 8 in FIG. 1.

(Continued)

The broken lines illustrate portions of the rail vehicle that form no part of the claimed design.
